UNITED STATES PATENT OFFICE.

HARRY A. DAVIS, OF HOPEDALE, MASSACHUSETTS, ASSIGNOR TO DRAPER CORPORATION, OF HOPEDALE, MASSACHUSETTS, A CORPORATION OF MAINE.

LAY-ROCK-SHAFT BEARING FOR LOOMS.

Application filed March 18, 1924. Serial No. 700,016.

To all whom it may concern:

Be it known that I, HARRY A. DAVIS, a citizen of the United States, and resident of Hopedale, in the county of Worcester and 5 State of Massachusetts, have invented an Improvement in Lay-Rock-Shaft Bearings for Looms, of which the following description, in connection with the accompanying drawings, is a specification, like characters 10 on the drawings representing like parts.

This invention relates to looms and more particularly to the lay rock-shaft bearings.

The constant rocking movement of the lay rock-shaft during weaving produces 15 wear and lost motion between the shaft and its bearings which in time admits objectionable play resulting in imperfect weaving. The wear upon the bearings, due to the weight of the rocking parts, occurs at the 20 lower portion of the bearings. Heretofore various expedients have been suggested for overcoming the objections incident to the wear of the rock-shaft and its bearing, but the present invention differs from these in 25 that the lay-rock-shaft itself is relieved from all wear, and transmit such wear to other parts that may be readily adjusted to compensate for wear, and inexpensively renewed.

30 The present invention, among other advantages, provides a cheap and simple bearing which may be readily adjusted to present new wearing surfaces between the operating parts and eliminates wear on the lay rock-shaft itself.

35 The invention will best be understood from the following description and accompanying drawings of one good, practical form thereof.

40 In the drawings:

Fig. 1 is a perspective view of a portion of a loom and the lay rock-shaft with the present invention associated therewith.

45 Fig. 2 is a perspective view of the bearing showing the parts in spaced relation.

Fig. 3 is an enlarged vertical sectional view through one bearing for the lay rock-shaft; and

50 Fig. 4 is a sectional view taken on the line 4—4 of Fig. 3.

The loom frame 1, may be of any usual construction and as shown the lay rock-shaft 2 is supported near the lower portion of the side frames of the loom for rocking movement. Secured to the lay rock-shaft 2 are

the lay swords 3 which are provided with the hub portions 4 that receive and are rigidly secured to the lay rock-shaft. The upper portion of the lay swords 3 support the usual lay (not shown) which is actuated as usual 60 with a back and forth movement by a crank-shaft or other going part of the loom, the construction being such that as the lay is actuated during weaving it moves toward 65 and from the front of the loom to beat up 65 the weft in a well known manner.

The present lay rock-shaft 2, as is usual, is provided at each end with a shoe 5 that supports the picker stick 6.

Each of the side frames 1 of the loom is 70 provided with an opening 7, as usual, and, as shown in the present instance, a box plate 8 having elongated bolt openings near its ends is adjustably secured, preferably to the outside of each side frame of the loom by 75 bolts 9. The box plate 8 has extending inwardly therefrom a bearing sleeve 10 extending through the opening 7 of the side frame inwardly thereof.

In accordance with the present invention 80 the lay rock-shaft 2 is provided near each end with a bushing 11 which may be rigidly secured to the lay rock-shaft in different positions of adjustment and extends into the bearing sleeve 10, the arrangement being 85 such that the bushing rocks with the lay rock-shaft, so that the wear will occur between the bushing 11 and sleeve 10.

As stated, the greatest wear occurs at the 90 lower portion of the operating parts, and in accordance with the present invention the bushing 11 is adapted to be rotated upon the lay rock-shaft 2 through a desired angle so that, when one portion of the bushing 11 becomes worn at its lower side, the bushing 95 may be rotated to bring a different portion to the under side of the lay rock-shaft. The sleeve 10 is preferably formed of harder metal than the bushing 11, so that most of the wear will occur upon the latter, and 100 the bushing 11 is shown as having a head 12 at one end which forms a shoulder that abuts against the inner end of the sleeve 10.

Various means may be provided for rigidly securing the bushing 11 to the lay rock-shaft in different positions of angular adjustment, and in the construction shown the clamping means consists of a bolt 13 that is mounted in a bore extending through the head 12 transversely of the bushing. The 110

bolt 13 has a notch 14 formed in one side that receives the curved face of the lay rock-shaft, and the bushing is clamped to the lay rock-shaft in any desired position by 5 tightening the nut 15 at one end of the bolt 13. This serves to force the notched portion of the bolt against the curved face of the lay rock-shaft with clamp effect.

It is important that the operating surfaces 10 of the bearing be properly lubricated, and to this end the box plate 8 is provided with an oil receptacle 16 having an opening 17 leading to the bushing 11, and the bushing preferably has a groove 18 extending longitudinally of its face to conduct oil lengthwise 15 thereof.

When the lower portion of the bushing 11 becomes worn, due to the rocking movement 20 of the lay, the clamping nut 15 may be unscrewed, whereupon the bushing may be rotated upon the lay rock-shaft to bring a new portion into the field of greatest wear and the bushing is then clamped in this new position by tightening the nut 15.

It is desirable to provide means for indicating the different positions to which the bushing 11 should be rotated in taking up the wear, and to this end, in the present case, the head 12 is provided with the raised 25 indexes "I", "II" and "III" shown, formed by raised ribs corresponding to the Roman numerals and indicating the successive positions to which the bushing should be rotated in taking up wear. It will be understood, however, that the indexing means 30 may be variously formed and may indicate either more or less than the three positions of adjustment indicated in the drawing, but it is desirable that the indexes be formed 35 so that they will not be readily hidden by dirt or grease.

In assembling the bearing of the present invention the bushing 11 will be secured in the position shown in Fig. 4 with the index 40 "I" in the uppermost position, and when the bushing becomes worn it may be rotated to bring the index "II" in the uppermost position, and when it is again adjusted the index "III" will be rotated to the uppermost position. After the bushing has become worn in each of these positions, it may be discarded for a new bushing. The bushing 11 preferably is provided with three oil grooves 18 positioned so that one will 45 align with the oil opening 17 for each position of bushing adjustment, and if desired holes 19 may be formed at the bottom of the grooves 18 to increase their oil capacity.

It is apparent that the bushing 11 may be 50 adjusted with a fair degree of accuracy to the different predetermined positions indicated by the indexes "I", "II", and "III" by simply turning the bushing until an index appears to be in its uppermost position, but in order to rotate the bushing accurate-

ly to the desired position so that an oil groove 18 will align with the oil opening 17, indicating means should be provided on the bearing sleeve 10 with which the indexes upon the head 12 may align. The sleeve 10 70 is therefore shown as provided upon its outer face with three ribs 20 spaced in conformity with the ribs forming index "III" and raised sufficiently to prevent them from becoming readily obscured by dirt or grease. 75 It should be noted that the two ribs forming the index "II" are spaced the same distance apart as the outer ribs of the index "III". This enables the two ribs of the index "II" to be alined with the outer ribs 80 forming the indicating means 20, and when the index "I" is in its uppermost position, it may be alined with the middle rib of the indicating means 20.

What is claimed is:

1. In a loom, the combination of the oscillatory lay rock-shaft, lay swords secured to the lay rock-shaft, a bushing mounted on the lay rock-shaft, means for securing the bushing to the lay rock-shaft in different rotative positions that the bushing may rock with the lay rock-shaft in its different positions of angular adjustment, including a bolt having a notched side that engages the curved face of the lay rock-shaft, and means for forcing the bolt in the direction of its length with clamping effect, and a plate secured to the loom frame and having a bearing sleeve in which the bushing is journaled.

2. In a loom, the combination of the lay rock-shaft, lay swords secured to the lay rock-shaft, a bearing sleeve secured to the loom frame, a bushing mounted on the lay rock-shaft and journaled in said sleeve, means for rigidly securing the bushing upon the lay rock-shaft in different positions of angular adjustment so that the bushing will rock with the lay rock-shaft in its different positions of adjustment, indexes disposed about the bushing to indicate different positions of angular adjustment of the bushing upon the lay rock-shaft, and indicating means upon the bearing sleeve with which the different indexes may be alined.

3. In a loom, the combination of the lay rock-shaft, lay swords secured to the lay rock-shaft, a bearing sleeve secured to the loom frame, a bushing mounted on the lay rock-shaft and journaled in said sleeve, means for rigidly securing the bushing upon the lay rock-shaft in different positions of angular adjustment so that the bushing will rock with the lay rock-shaft in its different positions of adjustment, cooperating indexes upon the bushing and bearing sleeve and disposed in angularly spaced relation about one of them to indicate different positions of angular adjustment of the bushing within said sleeve.

4. In a loom, the combination of the lay rock-shaft, lay swords secured to the lay rock-shaft, a bearing sleeve secured to the loom frame, a bushing mounted on the lay rock-shaft in position to rotate in said sleeve and having oil grooves formed in its outer face in spaced angularly disposed relation, means for securing the bushing rigidly to the lay rock-shaft in different positions of angular adjustment so that the bushing will rock with the lay rock-shaft when secured in its different angular positions, and indexing means for designating the different positions of angular adjustment of the bushing within the bearing sleeve when the bushing is turned to compensate for wear and at the same time bring the different oil grooves into oil receiving positions.
5. In a loom, the combination of the lay rock-shaft, lay swords secured to the lay rock-shaft, a bearing sleeve secured to the loom frame, a bushing mounted on the lay rock-shaft and journaled in said sleeve, means for rigidly securing the bushing upon the lay rock-shaft in different positions of angular adjustment so that the bushing will rock with the lay rock-shaft when secured in its different angular positions, and cooperating indexes upon the sleeve and bushing for indicating different predetermined positions of angular adjustment of the bushing when it is turned within the bearing sleeve to compensate for wear.

In testimony whereof, I have signed my name to this specification.

HARRY A. DAVIS.
